UNITED STATES PATENT OFFICE.

JOHN MAGEE, OF DETROIT, MICHIGAN, ASSIGNOR TO DIAMOND POWER SPECIALTY COMPANY, OF DETROIT, MICHIGAN, A CORPORATION OF MICHIGAN.

BLOWER FOR BOILERS.

1,185,816.

Specification of Letters Patent. Patented June 6, 1916.

Application filed April 5, 1915. Serial No. 19,100.

To all whom it may concern:

Be it known that I, JOHN MAGEE, a citizen of the United States of America, residing at Detroit, in the county of Wayne and State of Michigan, have invented certain new and useful Improvements in Blowers for Boilers, of which the following is a specification, reference being had herein to the accompanying drawings.

10 In water tube boilers of the upright type in which an upper drum is connected to a lower drum by upright water tubes, and upright baffles are used to conduct the gases of combustion longitudinally of the tubes 15 up one pass formed by the baffle and down the next pass, it is desirable to provide cleaning agents that will prevent the precipitation of soot to any extent against the baffle and will aid in propelling the soot 20 toward the smoke exit. In boilers of this type in which the gases of combustion are introduced near the lower drum from the combustion chamber, usually from a lateral inlet, it is somewhat difficult to maintain 25 such cleaning members near the point of entrance of the gases because of the extreme heat of the latter. In certain types of cleaners or blowers this may be accomplished by having the blowers withdrawable from the path of the gases. This 30 necessitates a certain amount of space outside of the boiler to permit of the withdrawal of the cleaning members.

This invention relates to soot blowers for 35 boilers of the type above described, in which a series of blower units are mounted on either face of the upright baffle or baffles which form the boiler passes both at points distant from the entrance of the extremely hot gases from the combustion 40 chamber and directly at this point, but in such a way as to be effective without being in the direct path of the gases. The blower as a whole is so disposed as to be effective 45 in aiding the draft as well as propelling the soot and dislodged matter along the path of the draft and therefore through the outlet.

The invention consists in the matters 50 hereinafter set forth, and more particularly pointed out in the appended claims.

In the drawings, Figure 1 is a view, par-

tially in longitudinal upright section and partially in elevation, of a boiler equipped with a blower that embodies features of 55 the invention; Fig. 2 is an enlarged cross sectional view of the boiler shown in Fig. 1.

Referring to the drawings, a boiler which is known commercially as the "Wickes" type, consists of an upper steam drum 1 and 60 a lower member 2 connected by upright water tubes 3 and mounted in an external setting 4 of suitable design. Gases of combustion from the furnace chamber 5 enter the setting at the opening shown at 6 and 65 are directed upwardly by a central upright baffle 7 that is disposed transversely across the setting and is usually held in position by the adjacent contacting series of water tubes indicated at 9 in Fig. 2. The gases 70 pass over an opening between the top of the baffle and the upper drum 1 and downwardly and out through a smoke outlet 10 just above the lower drum or shell 2. As a result of this construction the gases from 75 the combustion chamber do not impinge at exactly right angles against the baffle opposite the throat opening 6 but tend to swing upwardly in substantially the manner indicated by the arrows, thereby leaving 80 what may be called a dead air or gas space in the lower angle.

A series of blower units is arranged along the face of the baffle in the pass and along the corresponding side of the baffle 85 in the down pass so as to command the inner surfaces of the passes and to direct cleaning jets along the baffle faces. A rotatable jet pipe is mounted in the lower dead space formed above the lower drum 2 and 90 the baffle and is made up of a horizontal pipe 12 whose outer end is journaled in a suitable bearing head 13 and whose steam intake end portion is rotatable in a suitable housing 14, the members 13 and 14 being 95 properly adjusted in the setting. A suitable steam connection 15 with a steam line 16 whereby the pipe may be revolved as through the medium of a hand wheel 17 or the like, provides means for introducing 100 steam under pressure either from the boiler itself or other suitable source of supply, or air under pressure from a suitable supply. A series of jet nozzles extend laterally from

the pipe 12 and may be turned outwardly or upwardly so as to direct the cleaning jets between the banks of water tubes and along the latter and upwardly along the 5 baffle in the direction of draft.

An intermediate pipe 18 likewise provided with lateral jets and with suitable steam connections, and rotatably mounted in the setting, is placed adjacent the corresponding 10 face of the baffle above the pipe 12 and a similar pipe 19 with lateral jets is also disposed across the setting adjacent the baffle near the upper end thereof. Since these pipes are rotatable to adjust the jets therefrom to move upwardly in the direction of the draft, they thereby assist the draft to 15 propel soot and other matter that has been previously blown from the water tubes by the jets as the blower units are turned, and 20 so cause the soot to be carried over and enter the down pass. Blower units 20, 21 and 22 are similarly disposed along the fan of the baffle so as to command the interior surfaces of the down pass, the proximate 25 baffle face and the water tubes and blow the soot not only from the tubes but when dislodged drive it forward along the direction of the draft, the lowest unit being in the angle of the baffle and bottom drum so that 30 the soot may be driven directly through the lateral outlet.

Preferably the upper pipes may be manipulated from the floor by means of chains or like means suitably mounted on hand wheels. 35 In operation the pipes may be severally operated to dislodge the soot, preferably starting with the unit which is nearest the gas intake and then in succession up the face of the baffle and then down the face of the 40 baffle in the down pass so that the soot is first stirred up and then projected in the direction of the draft, thereby being ejected through the smoke outlet. The disposition of the lower members in the angles of the 45 baffle and lower drum prevents the lodgment of soot in the angles while at the same time the unit that is on the intake side of the baffle at this point is so disposed as not to be affected by the incoming hot gases which 50 pass above it and do not tend to burn it out.

Obviously, changes in the detail of construction may be made without departing from the spirit of my invention and I do not care to limit myself to any particular 55 form or arrangement of parts.

What I claim is:

1. A soot blower for boilers having upper and lower members connected by upright water tubes and divided by a baffle into an 60 up-pass and a down-pass with gas intake near the lower end of one pass and smoke outlets near the lower end of the other pass, comprising a series of rotatable jet pipes journaled across the pass spaces at points

along the upface and down-face of the baffle 65 and adapted to direct jets against the interior surfaces of the boiler and along and over the tubes and baffles in the general direction of draft.

2. A soot blower for boilers having upper 70 and lower steam drums connected by upright water tubes and divided by a baffle into an up-pass and a down-pass with gas intake near the lower end of the up-pass and a smoke outlet near the lower end of the 75 other pass, comprising a series of angularly adjustable jet pipes mounted across the passes at points along the up-face and down-face of the baffle adapted to be arranged to direct jets simultaneously in the general 80 direction of the draft in both passes.

3. A soot blower for boilers having upper and lower steam drums connected by upright water tubes and divided by a baffle into an up-pass and a down-pass with gas intake near the lower end of the up-pass and a smoke outlet near the lower end of the other pass, comprising a series of angularly adjustable jet pipes mounted across the 85 passes at points along the up-face and down-face of the baffle adapted to be arranged to direct jets simultaneously in the general 90 direction of the draft in both passes, the jet pipe adjacent the gas inlet in the up-pass being disposed out of the general path of 95 the products of combustion as they enter the pass from the inlet.

4. A soot blower for boilers having upper and lower steam drums connected by upright water tubes and divided by a baffle 100 into an up-pass and a down-pass with gas intake near the lower end of the up-pass and a smoke outlet near the lower end of the other pass, comprising a series of angularly adjustable jet pipes mounted across the 105 passes at points along the up-face and down-face of the baffle adapted to be arranged to direct jets simultaneously in the general direction of the draft in both passes, the jet pipe adjacent the gas intake being disposed 110 in the angle between the lower boiler member and the baffle out of the direct path of the products of combustion entering through the gas intake.

5. The combination of a boiler having an 115 upper drum, a lower drum, water tubes connecting the drums, a setting inclosing the drums and tube-space with a gas inlet and a gas outlet adjacent the upper face of the lower drum, and an upright baffle extending 120 across the setting between the inlet and outlet and forming an up-pass from the inlet and a down-pass to the outlet, with a soot blower consisting of a series of angularly adjustable jet pipes across the passes adjacent the up-face and the down-face of the baffle, provided with lateral jet openings for 125 directing jets over the pass and baffle sur-

faces and water tube and adapted to coöperate to move dislodged material in the general direction of draft, the first pipe of the series being disposed in the angle between the 5 baffle and lower drum adjacent the inlet and out of the general path of gases entering the inlet, and the last pipe of the series being disposed in the angle of the baffle and lower

drum in the down-pass for directing jets directly toward the outlet. 10

In testimony whereof I affix my signature in presence of two witnesses.

JOHN MAGEE.
